Primary Examiner—Ruth McInroy*Attorney, Agent, or Firm*—Fulbright & Jaworski L.L.P.[57] **CLAIM**

The ornamental design for a multiple beam antenna, as shown and described.

DESCRIPTION

FIG. 1 is a perspective view of a multiple beam antenna showing our new design;

FIG. 2 is a side elevational view thereof;

FIG. 3 is a top plan view thereof; and,

FIG. 4 is a bottom plan view thereof.

The pole (FIGS. 1,2 and 4) and pole mounting (FIG. 4) are shown in broken lines for illustrative purposes only and form no part of the claimed design.
